AUTOMATIC ROWBOAT

Henry S. Noddings, Washington, D. C.

Application February 2, 1935, Serial No. 4,706

9 Claims. (Cl. 46—92)

The present invention relates to boats and the primary object of the invention is to provide a power operated toy row boat embodying mechanism for mechanically imparting rowing movement to the oars for propelling the boat.

A further object of the invention is to provide a means whereby the oars are adjustable for regulating the length of the stroke, the dip of the blade, and also the leverage of the oars so as to obtain maximum propelling force to the boat by the oars.

A further and important object resides in the arrangement for actuating the oars whereby the oar blades are moved thru an elliptical path of movement during the rowing action.

A still further object resides in the arrangement whereby the simulation of an oarsman grasping the handle portions of the oars is so associated with the oar operating mechanism as to have a realistic rowing motion imparted thereto as the oars are operating.

Other objects and advantages of the invention will be apparent from the following detailed description, taken in connection with the accompanying drawings forming a part of this specification and in which drawings:—

Figure 1 is a perspective view showing the automatic rowing means applied to a boat.

Figure 2 is an enlarged longitudinal section thru one of the oars showing its various adjustments and the mounting therefor.

Figure 3 is an enlarged fragmentary perspective view showing the adjustable connection for the inner ends of the oar blades.

Figure 4 is an enlarged fragmentary detail view of the oar operating means.

Figure 5 is an enlarged fragmentary detail view showing the adjustable crank arm on the crank disc for varying the throw of the connecting rods.

Figure 6 is an enlarged section on the line 6—6 of Figure 5.

In the drawings, and wherein like reference characters designate corresponding parts throughout the several views, the letter A designates a boat of any preferred type upon which the improved rowing apparatus has been shown mounted. The letter B may designate a suitable motor for actuating the oar operating means or mechanism C for mechanically operating the oars designated as a whole by the letter D. The letter E designates the figure of an oarsman associated with the oar operating means.

The motor B may be of any preferred type and in the example shown is an electric motor receiving its source of current from a suitable bat-

tery 5. The motor B operates a drive shaft 6 suitably journaled at one end in the motor framing and extending longitudinally of the boat with its forward end mounted in a suitable bracket and embodying a worm 7 adapted to mesh with a worm gear 8. This worm gear 8 is fixed upon a crank shaft 9 extending transversely of the boat and journaled in suitable brackets 10. Fixed upon one end of the crank shaft 9 outwardly of the supporting brackets 10 is a crank disc 11 to which the oar operating means C is connected for operation. When the boat is traveling forward, the direction of rotation of the crank disc 11 is in the direction of the arrows shown in Figures 1 and 4.

The oar operating means or mechanism C comprises a connecting rod 12 which is upwardly offset adjacent its rear end as clearly shown in Figures 1 and 4. Adjustably mounted upon the outer face of the crank disc 11 as by means of a set screw 13 is a crank arm 14. Carried by the free end portion of the crank arm 14 is a shouldered set screw 15 providing a crank pin or stud for pivotal connection with the rear end of the connecting rod 12. As shown by the dotted line 25 position of the crank arm 14, and the dot and dash line circles in Figure 5, the crank arm 14 may be adjusted with respect to the axis of the crank shaft 9 so as to vary the throw of the crank pin 15. This adjustment of the crank arm 14 may be made by loosening the set screw 13 forming the pivotal axis for the crank arm. The connecting rod 12 extends forwardly from the crank pin 15 at the longitudinal center of the boat and is provided at its forward portion with a series of adjustment openings 16 for receiving an adjustment pin 17. Pivoted at its lower end as upon a pivot bracket 18 to swing forwardly and rearwardly of the boat is a rock lever 19 which is also provided at its lower portion with a series of adjustment openings 20 which also receive the adjustment pin 17. The purpose of providing this adjustable connection between the connecting rod 12 and rock lever 19 will be subsequently described.

Referring now to the specific construction and mounting of the oars D, the oars are each of identical construction and each embodies a blade section 21 provided at its inner end with a radially corrugated connector plate 22 as shown in Figure 3.

The blade 21 is adapted for adjustable connection to the outer end of a coupling portion 23 which is pivotally mounted intermediate its ends as by a pivot pin 24 in the upper end of a sleeve 55

25. The outer end of the coupling portion 23 is provided with a threaded bore 26 for receiving the threaded shank of an adjusting stem 27. The outer end of this adjusting stem 27 is formed 5 with a radially corrugated connector plate 28 as shown in Figure 3 for co-acting with the connector plate 22 of the oar blade. An adjusting screw 29 extended thru the axial center of the connector plates 22 and 28 serves to secure the 10 blade in various angular adjusted positions with respect to the adjusting stem 27. Thus it will be seen that this manner of adjustably mounting the blades 21 allows for the dip of the blades to be regulated. A lock nut 30 on the threaded 15 shank of the adjusting stem 27 may be turned into engagement with the outer end of the coupling portion 23 to secure the stem against rotation and this manner of connecting the blade to the coupling portion permits feathering of the 20 blades. The inner end of the coupling portion 23 is formed with a threaded shank 31 for threading into the threaded bore of a handle portion or section 32. A lock nut 33 on the shank 31 serves to retain the handle portion 32 in longitudinally 25 adjusted position on the shank 31. The inner end of the handle section 32 is formed with a ball end 34 as shown more clearly in Figure 2. The ball ends 34 of the oars are intended to extend into tubular sockets 35 and 35' secured 30 in axial alignment upon the connecting rod 12. These elongated tubular sockets 35 and 35' slidably receive the ball end 34 of respective oars and preferably have the outer ends of their bores tapered as shown in Figure 2 to prevent any binding 35 between the handle sections and the sockets. The tubular sockets 35 and 35' are separably connected in axial alignment preferably by means of a threaded stem 36 on the inner end of the socket 35' extended thru adjustment openings 37 in the connecting rod 12 and threaded into the inner end of the socket 35. The adjustment openings 37 permit adjusting the tubular sockets 35 in a direction longitudinally of the connecting rod.
40. The oars D are mounted upon adjustable oar mounting or locks 38 secured one to each side of the boat. These adjustable oar mountings or locks 38 comprise a slotted mounting plate 39 secured to the boat by means of a screw or the like 40 passed thru the slot in the plate so as to permit the plate being adjusted in a direction transversely of the boat. Projecting upwardly from the outer end of the mounting plate is a pivot stud or post 41 for slidably receiving the 45 sleeve 25 whereby the sleeve is permitted to pivot on the post 41. Thus the post 41 and the pivot pins 24 provide means permitting horizontal and vertical swinging movement of the oars during the rowing action.
50. It is preferred that a figure simulating an oarsman be associated with the oar operating means and this figure may be of any suitable material and as will be observed is arranged with the body portion disposed over the rock lever 19. The forward and backward swinging of the lever 19 will impart a rocking movement to the body. The arm portions of the body are arranged to give the appearance of holding to the handle portions of the oars. A framing is provided for the arm portions 55 of the figure and this framing preferably embodies an inverted U-shaped wire member having its cross piece 44 pivoted intermediate its ends in the upper portion of the rock lever 19 and its arm portions 45 extending downwardly at opposite sides of the rock lever. The framing for the

forearms of the figure preferably comprise a V-shape wire member connected at its apex as at 46 to the forward portion of the connecting rod 12 and with the arm portions 41 extending in diverging relation toward the rock lever. The 5 free ends of the arm portions 41 are formed with loops or eyes 48 which slidably receive with a loose fit the arms 45. Thus, by having the body carried by the rock lever, the body will rock forwardly and rearwardly with the rock lever, and by having the V-shaped framing member secured to the connecting rod 12, the arms of the figure will be folded and straightened during the rowing action to present a more realistic appearance.

15

In operation of the mechanism for imparting rowing movement to the oars D, when the crank disc 11 is rotating in the direction of the arrow shown in Figure 4, the tubular sockets 35 and 35' will move thru an elliptical path as indicated by 20 the dot and dash line 50 in Figure 4. This path of movement of the tubular sockets will impart a corresponding elliptical path of movement to the blades 21. With this elliptical path of movement of the blades 21, it will be noted that the 25 blades will be engaging the water for a considerable degree of rotation of the crank disc. This elliptical path of movement of the blades is provided by the particular arrangement for mounting opposite ends of the connecting rod 12.

30

As the oars are moved thru a rowing motion by the connecting rod 12, the ball ends 34 of the oars will be permitted to move inwardly and outwardly in their respective sockets 35 and 35'. The up and down movement of the blades at the 35 ends of the stroke will be provided by the raising and lowering of the connecting rod 12 due to the action of the crank pin 15.

Referring now to the various adjustments of the mechanism for obtaining maximum propelling force to the boat by the oars under varying conditions, without adjusting the connection between the connecting rod 12 and the rock lever 19, the length of the stroke may be adjusted by 40 loosening the set screw 13 and swinging the crank arm 14 to vary the throw of the crank pin or stud 15. Considering Figure 5, when the crank arm 14 is swung from the full line position shown to the dotted line position shown, the stroke of the crank pin 15 will be lessened and thus shorten the 45 length of the stroke of the oars. This adjustment of the crank arm 14 will also to some extent regulate the dip of the blades. By raising the forward end of the connecting rod 12 to a higher position on the rock lever 19 will raise the elliptical path 50 and cause the blades to dip deeper into the water. When adjusting the connecting rod along the rock lever by the adjustment openings 20, it may also become necessary to adjust the connecting rod with respect to the rock lever 55 50 by means of the adjustment openings 16 so as to obtain the proper position for the figure E. When desiring to increase the leverage of the oars, the screws 40 are loosened and the mounting plate 39 moved inwardly for shortening the space between 60 the connecting rod and the pivot stud 41. This inward movement of the mounting plate will of course necessitate loosening of the lock nut 33 and threading the shanks of the coupling portions 23 into the handle sections 32 so as to shorten the 65 space between the ball ends 34 and the pivot pins 24. Feathering of the blades 21 may be accomplished by loosening the lock nuts 30 and rotating the stems 27 for disposing the blades at the desired feathering position. The blades may be 70 75

adjusted to vary the dip of the blades by means of the bolt 29 co-acting with corrugated connector plates 22 and 28. Thus it will be seen that the various adjustments provide for obtaining maximum rowing efficiency.

Changes in details may be made to the shape, size and arrangement of parts without departing from the spirit of the invention or the scope of the following claims.

10 I claim:

1. In a rowing device of the class described, a pair of oars, a connecting rod provided intermediate its ends with laterally opening sockets slidably receiving the inner ends of the oars, a pivotally mounted lever having pivotal connection with one end portion of the connecting rod, and drive means connected to the other end of the connecting rod for imparting a circular path of movement to said other end.

2. In a row boat, a pair of pivoted oars having handle portions, a crank shaft, means for imparting rotation to the crank shaft, a crank pin on the crank shaft, a connecting rod pivoted at one end on the crank pin, a rock lever, means pivotally connecting the other end of the connecting rod to the rock lever, and tubular sockets carried by the intermediate portion of the connecting rod and slidably receiving the handle portion of said oars.

3. In a rowing device for boats, a pair of pivoted oars, a crank shaft, means for imparting rotation to the crank shaft, a crank pin carried by the crank shaft, means for adjusting the throw of the crank pin, a connecting rod connected at one end on the crank pin, a rock lever, means adjustably and pivotally connecting the other end of the connecting rod to the rock lever, and socket coupling means between the inner ends of the oars and the connecting rod.

4. In a rowing device for boats, a pair of pivoted oars each having a handle portion, a crank disc, means for rotating the crank disc, a crank arm adjustable on the crank disc and having a crank pin, a connecting rod pivoted at one end on the crank pin, a rock lever, means adjustably and pivotally connecting the other end of the connecting rod to the rock lever, a pair of axially aligning tubular sockets carried by the connecting rod, and a ball end on the handle portion of each oar for engaging in said sockets.

5. In a rowing device, in combination with a boat, a pair of oars pivoted one upon each side of the boat, a crank disc journaled on an axis transversely of the boat, means for rotating the

crank disc, a crank pin carried by the crank disc, a connecting rod pivoted at one end on the crank pin to extend longitudinally of the boat and having a series of adjustment openings at its other end, a rock lever pivoted on the boat and having a series of adjustment openings, means adjustably connecting said rod and lever at the adjustment openings, and sockets carried by the connecting rod for receiving the inner ends of said oars.

6. In a rowing device, in combination with a boat, an oar lock at each side of the boat and adjustable transversely of the boat, an oar pivotally mounted in each oar lock and adjustable therewith and each oar having an extensible handle portion inwardly of the oar lock, an oar operating member, and tubular sockets adjustably carried by the oar operating member and slidably receiving the inner ends of said handle portions.

7. In a rowing device, in combination with a boat, an oar lock at each side of the boat and adjustable transversely of the boat, an oar pivotally mounted in each oar lock, each oar having an extensible handle portion inwardly of the oar locks and a radially and angularly adjustable blade outwardly of the oar locks, an oar operating member, and tubular sockets carried by the oar operating member for receiving the inner ends of said handle portions.

8. An oar comprising a coupling portion having a threaded socket opening at its outer end and a threaded shank at its inner end, a handle threaded on said shank, an adjusting stem threaded into said socket and having a connector plate at its outer end, a lock nut threaded on the stem for adjustably securing the stem against rotation in the socket, a blade having a connector plate at its inner end for engagement with the connector plate on said adjusting stem, and an adjustment bolt connecting said connector plates.

9. In a toy row boat, a pair of pivoted oars, a connecting rod for operating the oars, a rock lever pivotally connected to one end of the rod, a framing member pivoted on the lever, a framing member connected at one end to the connecting rod and having sliding connection with the first mentioned framing member, and a figure associated with the lever and framing members, said lever and framing members imparting movement to the figure with a rowing action.

HENRY S. NODDINGS.
